Primary Examiner — Lucy Lieberman(74) *Attorney, Agent, or Firm* — Seager, Tufte & Wickhem LLC(57) **CLAIM**

The ornamental design for an electronic timer housing, as shown and described.

DESCRIPTION

FIG. 1 is a perspective view of the electronic timer housing;
 FIG. 2 is a front elevation thereof;
 FIG. 3 is a left side elevation thereof;
 FIG. 4 is a right side elevation thereof;
 FIG. 5 is a top plan view thereof; and,
 FIG. 6 is a bottom plan view thereof.

The portions illustrated in broken lines on the figures are for illustrative purposes only and form no part of the claimed design.
